MOTOR BASE FOR LIQUEFIER

Alfred J. Huck, St. Louis, Mo., assignor to Knapp-Monarch Company, St. Louis, Mo., a corporation of Delaware

Application September 14, 1953, Serial No. 26,792

Term of patent 14 years

(Cl. D89—1)

Fig. 1 is a perspective view of a motor base for liquefier, showing my new design.

Fig. 2 is a front elevational view thereof.

Fig. 3 is a side elevational view thereof, and

Fig. 4 is a top plan view thereof.

The design for the motor base disclosed is characterized by the combination of the name plate and control knob thereon having the configurations shown.

I claim:

The ornamental design for a motor base for liquefier, substantially as shown described.
